SLIDE FASTENER STOP
Louis H. Morin, Bronx, N.Y.
(125 Beechwood Ave., New Rochelle, N.Y.)
Filed Oct. 10, 1963, Ser. No. 315,207
3 Claims. (Cl. 24—205.11)

This invention relates to separable fastener stringers, wherein the coupling elements of the stringers comprise coils secured to a surface of the stringer tapes at adjacent edge portions of the tapes. More particularly, the invention deals with a novel type of separator for use in conjunction with stringers of the kind defined, wherein the box and pin members of the separator include interengaging elements, one of which includes means engaging a coil of one of the stringers in securely retaining the separator end of the stringers in coupled relationship with each other.

Still more particularly, the invention deals with a box member having means for angularly supporting the slider when brought into abutting engagement therewith to provide proper alignment of the pin part with the box part of the separator to facilitate free and easy coupling and uncoupling of the pin and box parts.

The novel features of the invention will be best understood from the following description, when taken together with the accompanying drawing, in which certain embodiments of the invention are disclosed and, in which, the separate parts are designated by suitable reference characters in each of the views and, in which:

FIG. 1 is a diagrammatic plan and sectional view of the box and pin structure of a pair of stringers illustrating initial engagement of the pin part with the box part in coupling the stringers.

FIG. 2 is a view, similar to FIG. 1, showing the pin part in a further advanced position in the box part.

FIG. 3 is a view, similar to FIGS. 1 and 2, showing the box and pin parts in elevation and illustrating a still further advanced position of the pin in the box part.

FIG. 4 is a view, similar to FIG. 3, showing the pin and box parts fully coupled and indicating, in part, the slider partially withdrawn from the pin and box parts.

FIG. 5 is a section substantially on the line 5—5 of FIG. 3 on an enlarged scale; and

FIG. 6 is a section substantially on the line 6—6 of FIG. 4 on an enlarged scale.

In the accompanying drawings, I have illustrated, in part, at 10, 10' part of a pair of stringer tapes, to one surface of which are secured coil fastener elements 11, 11' by stitching, as diagrammatically seen at 12, 12'. Looped ends of the coils project beyond the adjacent abutting edges of the tapes 10, 10', as clearly indicated by the abutting tapes at 13, projecting portions of the coils having offset interlocking elements 14, 14', as clearly illustrated in FIGS. 1 to 4, inclusive, no attempt being made to show these portions in the diagrammatic illustration of FIG. 6.

At 15 is shown the slider for coupling and uncoupling the stringers. The slider comprises two walls 16 and 17, note FIGS. 5 and 6, having side flanges 18 and 19, respectively, forming the contour of the channel of the slider body which diverges at the wide end 20 of the slider body, which end has, centrally thereof, the connecting web 21 separating the two channels, as with other structures of this type and kind.

The cross-sectional contour of the slider body is such as to bring the tapes into a position substantially centrally of the sides of the slider body, where the tapes pass through the side openings 22. It will also be apparent, from a consideration of FIG. 6, that the inner surface of the wall 16 of the slider is recessed, as seen at 23, to

2

clear the stitchings 12, 12', thereby preventing wear on the stitches in the operation of the slider along the stringers.

At the separator end of the fastener, the stringer tapes 10, 10' have their ends folded, as illustrated at 24, 24' in FIG. 5, and the tapes are reinforced by additional tapes 25, 25', which are stitched to the tapes 10, 10' including the folds 24, 24' therein. This construction locates the tapes 10, 10' in substantially the same relationship as the tapes as they appear in FIG. 6 of the drawing. Cast or otherwise secured on the end portions of the tapes 10, 10', including the reinforcements 25, 25', are box and pin parts 26, 27 of the separator.

The side portion of the stop or box part 26 secured to 10-25 includes an inwardly projecting reduced portion 28, having an integrally projecting hook 29, the hook forming a recess 30 on the inner surface thereof. The hook 29 projects from the surface 31 of the pin engaging socket or channel 32 of the box part 26, the channel 20 being partially defined by side flanges of the box part, one of which is seen at 33.

The pin part 27 has a rounded exposed surface 34 terminating at a recessed portion 35 in a rounded corner 36. The pin part 27 extends beyond the edge of the reinforcement 25' and has a projecting interlocking finger or lug 37, which partially forms the recess 35. The lug 37 has a rounded projection on one side surface thereof, as seen at 38, and a recess 39 on the opposed side surface thereof, 38 operating in conjunction with 30 the recess 30 and an end loop on the coil 11, or the element 14 thereof engages the recess 39, as seen at 14" in FIG. 4 of the drawing, when the pin and box parts and the stringers are coupled relationship to each other, this figure also clearly illustrating the engagements between 38 35 and 30 and the arrangement of the hook 29 within the recess 35. The box part 26, at its outer end, is generally of the contour clearly shown in FIGS. 3 and 4 of the drawing and is of greater thickness than the extension 28 thereon. This greater thickened portion has, on its inner surface, angularly disposed walls 40, against which the contracted single channel end of the slider operates, as will be later described.

Considering FIGS. 1 to 4, inclusive, it will be apparent that, in the operation of coupling the pin part with the box part, preparatory to engaging the stringers, the slider 15 is brought into engagement with one of the angular surfaces 40, as illustrated in FIG. 1 of the drawing, at which time the pin part is moved into the position, substantially as seen in said figure and, in continuing this inward movement of the pin part, the slider is swung from the position shown in FIG. 1 to a position substantially as seen in FIG. 2 and this movement is further continued until the lug 37 or the projection 38 thereon strikes the hook 29, as seen in FIG. 3 of the drawing. This checks coupling engagement of the pin part with the box part, after which the user operates the slider, moving the same from left to right or, in other words, from the position of FIG. 3 to the position of FIG. 4, in which last operation the slider moves the pin part 27 into coupled engagement with the box part or, in other words, with projection 38 on the lug 39 in engagement with the recess 30 on the hook 29 and with the element of the end loop of the coil 11 engaging the recess 30, as illustrated at 14". With the parts in this position, it will be apparent that the stringers are securely coupled against separation adjacent the pin and box parts.

In uncoupling the pin and box parts, it will be apparent that the slider is moved from the position of FIG. 4 into the position shown in FIG. 3, in which position the coils 11, 11' of the stringers are separated by the slider, after which the pin part 27 is withdrawn from the box part

or, in other words, moved from the position of FIG. 3 to the position of FIG. 2 and, then, finally out through the slider when the slider is in the position shown in FIG. 1. The above description describes the step fashion of continued operation between FIG. 1 and FIG. 3 and from FIG. 3 back to FIG. 1, it being understood that an independent operation is required to control movement of the slider from FIG. 3 to FIG. 4 and vice versa.

From the foregoing, it will be apparent that the wall 17 of the slider, including its flanges 19, operates on the stringer tapes; whereas, the wall 16 and its flanges 18 operate upon the coils 11, 11'. By minimizing the space between adjacent surfaces of the flanges 18 and 19, not only is the tape centrally located, but substantial thicknesses of the box and pin parts are made possible for engagement with the tapes, including the reinforcements 25, 25', as will be clearly apparent from a consideration of FIG. 5, the thicknesses illustrated being those of the pin part and the reduced extension 28 of the box part, upon which the contracted end of the slider operates. It will be understood that the reinforcing tapes 25, 25' are stitched or otherwise secured to the tapes 10, 10', including the folded-over portions 24, 24' and the stitchings are diagrammatically illustrated at 41, 41' in FIG. 5 of the drawing.

Considering FIG. 5 of the drawing, it will be apparent that the rounded corners of the pin part and the reduced extension 28 of the box part operating in conjunction with the rounded surfaces of the flanges 18 and 19 will provide for free movement of the pin part inwardly and outwardly through the box part and, in FIGS. 1, 2 and 3 of the drawing, clearances between 27 and 28 and the flanges 19 are illustrated by the dotted line showing of the flanges 19 in said figures, it being understood that the illustrations are diagrammatic.

For the purpose of this document, the right end of the pin and box, as seen in FIGS. 1-4, shall be considered the inner or inward end of these elements and the opposite or left end, as viewed in these figures, shall be considered the outer or outward end of these elements.

Having fully described my invention, what I claim as new and desire to secure by Letters Patent is:

1. In a device of the class described, having a pair of stringers carrying fastener elements, a slider having a constricted throat portion and diverging channels defined by top and bottom wings and a pair of flared side walls connected by a frog, each side wall comprising two parts separated by a slot to permit the movement of the stringers, said device also having a separable end connection for said stringers including a stop member to limit movement of the slider in one direction and a socket therein; the improvement providing means to prevent mismeshing of said fastener elements, said means comprising a pin joined to one of said stringers and adapted to pass through one of the channels of the slider and to engage in said socket, an inter-engaging projection and recess on said pin and stop member adapted to position said pin in said socket, a straight wall at the constricted throat portion of said slider disposed at right angles to the longitudinal axis of said slider, and angularly disposed walls on the inner end of the socket portion of said stop member which meet at a raised apex in the path of said slider midway of the width of said stop member to engage said straight wall on said slider and permit said slider to lean to one side of the longitudinal axis of said stop member to permit ready entrance of said pin through said slider into said socket of said stop member.

2. In a device of the character described, having a pair of stringers carrying fastener elements, a slider having a constricted throat portion and diverging channels defined by top and bottom wings, and a pair of flared side walls connected by a frog, each side wall comprising two parts separated by a slot to permit the movement of the stringers, said device having a separable end connection for said stringers including a stop member to

limit movement of the slider in one direction, and a socket therein; the improvement providing means to prevent mismeshing of said fastener element, said means comprising a box part and a pin part, the box being secured to one stringer tape and the pin part being secured to the companion stringer tape, the box part comprising an outer enlarged channel end forming a socket for reception of the pin part, an inner reduced end having a laterally projecting hook, including a recess on the surface thereof, the pin part having at its inner end a laterally projecting lug, outward of which the pin part includes a recess adapted to receive the projecting hook when the pin and box part are in coupled relationship to each other, said lug including a portion engaging the recess of said hook in keying the pin and box part against separation when in coupled relationship, and said lug including on a surface thereof a recess engaged by the coupling element on the stringer tape to which the box part is secured in further securing the stringers and pin box against separation.

3. In a device of the character described, having a pair of stringers carrying fastener elements, a slider having a constricted throat portion and diverging channels defined by top and bottom wings, and a pair of flared side walls connected by a frog, each side wall comprising two parts separated by a slot to permit the movement of the stringers, said device having a separable end connection for said stringers including a stop member to limit movement of the slider in one direction, and a socket therein; the improvement providing means to prevent mismeshing of said fastener element, said means comprising a box part and a pin part, the box being secured to one stringer tape and the pin part being secured to the companion stringer tape, the box part comprising an outer enlarged channel end forming a socket for reception of the pin part, an inner reduced end having a laterally projecting hook, including a recess on the surface thereof, the pin part having at its inner end a laterally projecting lug, outward of which the pin part includes a recess adapted to receive the projecting hook when the pin and box part are in coupled relationship to each other, said lug including a portion engaging the recess of said hook in keying the pin and box part against separation when in coupled relationship, said lug including on a surface thereof a recess engaged by the coupling element on the stringer tape to which the box part is secured in further securing the stringers and pin box part against separation, and a straight wall at the constricted throat portion on said slider disposed at right angles to the longitudinal axis of said slider and angularly disposed walls on the inner end of said stop member which meet at a raised apex in the path of said slider midway of the width of said stop member to engage said straight wall on said slider and permit said slider to lean to one side of the longitudinal axis of said stop member to encourage ready entrance of said pin through said slider into said stop member for engagement therewith.
